(57) CLAIM

The ornamental design for a drain cover, as shown and described.

DESCRIPTION

FIG. 1 is a front perspective view of a drain cover;

FIG. 2 is a bottom perspective view thereof;

FIG. 3 is a top view thereof;

FIG. 4 is a bottom view thereof;

FIG. 5 is left side view thereof;

FIG. 6 is a right side view thereof;

FIG. 7 is a front view thereof; and,

FIG. 8 is a rear view.

The broken line showing of fins and openings is included for the purpose of illustrating portions of the "article" and forms no part of the claimed design.
